US0D1057781S

(12) **United States Design Patent** (10) Patent No.: **US D1,057,781 S**
(45) Date of Patent: ** Jan. 14, 2025

(54) **CUTTING INSERT FOR MACHINE TOOLS
FOR METALWORKING**

(71) Applicant: **KORLOY INC.**, Seoul (KR)
(72) Inventors: **Sung Hun Kim**, Cheongju-si (KR);
Young Heum Kim, Cheongju-si (KR);
Tae Hee Cho, Cheongju-si (KR); **Sang
Yun Lee**, Cheongju-si (KR); **Ki Chan
Nam**, Cheongju-si (KR)

(**) Term: **15 Years**

(21) Appl. No.: **35/518,869**

(22) Filed: **Sep. 25, 2023**

(80) **Hague Agreement Data**

Int. Filing Date: **Sep. 25, 2023**
Int. Reg. No.: **DM/232540**
Int. Reg. Date: **Sep. 25, 2023**
Int. Reg. Pub. Date: **Nov. 3, 2023**

(30) **Foreign Application Priority Data**

May 24, 2023 (KR) 30-2023-0019906
